UNITED STATES PATENT OFFICE.

JENEROUS A. LONG AND CHARLES A. STURM, OF PORTLAND, OREGON.

OIL-BURNER.

1,369,897.

Specification of Letters Patent.

Patented Mar. 1, 1921.

Application filed November 24, 1919. Serial No. 340,119.

To all whom it may concern:

Be it known that we, JENEROUS A. LONG and CHARLES A. STURM, both citizens of the United States, residing at Portland, in the county of Multnomah and State of Oregon, have invented a new and useful Oil-Burner, of which the following is a specification.

Our invention relates to improvements in oil burners in which steam is mixed with the burning oil.

The objects of our invention are: to produce an apparatus which is simple to manufacture and to operate, which produces its own steam, injects the latter into the burning oil spray and thereby increases the heat of the flame, and which shuts off the supply of oil and water automatically in case the flame should accidentally become extinguished.

20 We attain these objects with the mechanism illustrated in the accompanying drawings, in which Figure I is a plan view of our device; Fig. II is a side view; Fig. III is a front view with the hand wheels of the 25 needle valves omitted; and Fig. IV is a sectional plan view of the complete burner tip. Similar numerals refer to similar parts throughout the several views.

Referring to Fig. I we have an oven, 30 range or furnace 1 of which 2 is the front wall and 3 is the bridge wall or baffle-plate, the latter being desirable with this burner in order to deflect the heat upward.

Attached to the front wall, within the 35 oven, is the burner tip 4 and the oil supply is furnished by gravity through the pipe 5, while water under pressure is supplied through the pipe 7. It will be noticed, however, that the water-supply pipe passes 40 through the flame in front of the tip whereby the water is converted into steam which mixes with the oil after issuing from the tip. Hand wheel 8 is part of a needle valve which 45 regulates the steam supply, while hand wheel 9 performs the same function in regards to the oil supply.

With this arrangement alone it may happen that the flame may accidentally become extinguished and the uninterrupted flow of 50 oil would collect at the bottom of the furnace to cause later an explosion when carelessly relighted. To obviate this danger the valves 10, 11 are inserted in the oil and water supply respectively. The valve stems

of both valves are connected by a link 12 55 and a thermostatic rod 13 is sent from the center of the link into the furnace near the path of the flame to be firmly supported at the rear of the baffle-plate 3. In this case the rear support for the thermostatic rod is 60 furnished by a bracket 14 which is attached to the baffle-plate although in some cases it may be possible to attach a bracket to the side wall of the furnace. However, care should be taken that the rear support 14 65 possesses a limited amount of flexibility so that the contraction of the thermostatic rod may not cause injury to the valves. Should the flame be accidentally extinguished, cold water instead of steam would issue from the 70 burner tip and, striking the thermostatic rod, would cause the valves of both oil and water supply to close automatically.

To enable the fireman, under these circumstances, to relight the fire, it becomes 75 necessary to by-pass the oil through the pipe 15 by opening the by-pass valve 16. After the flame has expanded the thermostatic rod and automatically opened the valves 10, 11 the by-pass valve 16 should be 80 closed. The valves 17, 18 are common shut-off valves. The by-pass is featured most clearly in Fig. III.

How the burner tip is constructed to serve the function of a needle valve becomes 85 instantly apparent from a contemplation of Fig. IV, and but little explanation is needed beyond designation of the various parts. The oil supply in the oil chamber 18 is regulated by the needle 19 which latter is 90 screwably mounted at the point 20. 21 is the stuffing gland for the valve. The steam supply in the steam chamber 22 is similarly regulated by a needle 23 having the thread 24, and being packed in the stuffing gland 25. To obtain an intimate mixture of oil and steam right at the point of egress required that the needle points should be placed together as close as possible, whereas the convenient operation of the hand wheels 100 8 and 9 demanded a certain distance between the latter, and for this reason the needles are set at an angle to each other, as shown.

Having thus described our invention, it 105 will be seen that our objects have been accomplished, and though we have shown the preferred form of construction, we reserve

to ourselves the right to make any changes which do not violate the spirit and principle of our invention.

We claim:

5. 1. In an oil burner, the combination of a furnace, a tip in the furnace, separate oil and water supplies terminating in the tip, a thermostatic rod within the path of the flame, slidingly operated valves between the tip and the source of the oil and water supplies, said valves being actuated by the thermostatic rod, and a manually operated 10 by-pass for the oil supply to by-pass the thermostatically controlled valve.
15. 2. In an oil burner, the combination of a furnace, separate oil and water supplies terminating in a needle valve within the furnace, and sliding cut-off valves interposed outside the furnace, with a thermostatic rod within the path of the flame, said rod actuating the cut-off valves, and a by-pass for the oil supply to circumvent the cut-off valve in said oil supply.
20. 3. In an oil burner, the combination of a furnace, with mechanism for burning a

mixture of fuel oil and steam in the furnace, said mechanism comprising pipes, needle valves, sliding cut-off valves, and a thermostatic rod traversing said furnace and operating the cut-off valves.

4. In an oil burner, the combination of a furnace, a baffle plate in the furnace, pipes leading into the furnace, sliding valves in the pipes, a link connecting the stems of the sliding valves, a flexible bracket attached 35 forwardly of the baffle plate, and a thermostatic rod in the path of the flame between said link and bracket.

5. In an oil burner, the combination with a furnace, a needle valve partly in the furnace, water and oil connections to the needle valve, the water connection passing through the effective spraying zone of the needle valve, a thermostatic rod subjected to the spray from the needle valve.

Signed by us at Portland, Oregon, this 45
19th day of November, 1919.

JENEROUS A. LONG.
CHARLES A. STURM.
